UNITED STATES PATENT OFFICE

ELMER H. ENGLEHORN, OF DOUGLASTON, NEW YORK

DESIGN FOR A RAILROAD-CROSSING SIGNAL

Application filed July 9, 1929. Serial No. 31,976. Term of patent 14 years.

To all whom it may concern:

Be it known that I, ELMER H. ENGLEHORN, residing at Douglaston, county of Queens, and State of New York, a citizen of the United States, have invented a new, original, and ornamental Design for a Railroad-Crossing Signal, of which the following is a specification, reference being had to the accompanying drawing, forming part thereof.

The drawing is an elevation of a railroad crossing signal embodying my design.

I claim:

The ornamental design for a railroad crossing signal, as shown.

ELMER H. ENGLEHORN.
